UNITED STATES PATENT OFFICE.

CHARLES O. HILER, OF OELWEIN, IOWA.

GRAVITY-CONVEYER.

No. 833,209.

Specification of Letters Patent.

Patented Oct. 16, 1906.

Application filed April 23, 1906. Serial No. 313,150.

To all whom it may concern:

Be it known that I, CHARLES O. HILER, a citizen of the United States, residing at Oelwein, in the county of Fayette and State of Iowa, have invented certain new and useful Improvements in Gravity-Conveyers; and I do declare the following to be a full, clear, and exact description of the invention, such as will enable others skilled in the art to o which it appertains to make and use the same, reference being had to the accompanying drawings, and to the figures of reference marked thereon, which form a part of this specification.

5 My invention relates to gravity-conveyers; and the object is to provide an efficient, durable, and portable device by which boxes of merchandise, freight, &c., may be moved by their own gravity from one place to another o in freight-houses, warehouses, stores, or on platforms, wharves, and even on the ground. This and other objects I attain by the novel construction and arrangement of parts illustrated in the accompanying drawings, in 5 which—

Figure 1 is a side elevation of a line of my conveyer with some boxes of goods on it. Fig. 2 is an enlarged top or plan view of a portion of Fig. 1. Fig. 3 is a diametrical o sectional view of one of the studs and two of the wheels used to support the boxes conveyed. Fig. 4 is a side elevation of one of the wheels seen at the left end of Fig. 2. Fig. 5 is a side elevation of the adjacent ends 5 of two of the supporting-rails detached from each other. Fig. 6 is a modified arrangement of the carrier-wheels.

Referring to the drawings by reference-numerals, 6 designates the floor, platform, or o ground, upon which is placed a row of suitable supports 7, which increase gradually in height from one end to the other. Upon said supports is placed a track made up of sections detachably hooked together, as indicated at 8. Each section of the track is made up of two flat rails secured together by transverse braces 10, which may be bolts with two nuts at each end or a flat bar riveted to the rails, as shown at 10 and 10^a, re- 5 spectively, in Fig. 2.

In the rails are secured studs 12, preferably having a shoulder 13 and a nut 14 to hold them firmly. Each stud is formed with an annular groove 15, meeting the grooves 16 in the wheels 17 and 18. Said grooves and the balls 19 therein form ball-bearings for

the wheels to revolve very easily on. Every other wheel is of the type 17, having a deep circumferential groove 20, which straddles the edge of the next wheel, which is of the 60 type 18. In this way the wheels are made to overlap each other, and thus to bring their tops as close together as possible to form an even supporting-line for the boxes 21, and still the wheels may be so large in diameter 65 that they revolve much easier than if made small enough to secure such short distance between their centers, and thereby between their tops, where the most possible unbroken supporting-line is desired, especially for the 70 transportation of small boxes. This advantage may also be attained by arranging the wheels zigzag, as in Fig. 6, in which case they would be all of the type 18.

The wheels may be cast in halves or integral and the ball-bearing formed in any suitable manner; but I prefer to stamp the wheels out of soft sheet-steel of the required thickness and draw them by dies into the shapes clearly shown in Figs. 3 and 4 and 75 80 then bolt the halves together, as at 23, in wheel 17 or rivet, as at 24, in wheel 18, (both in Fig. 3,) with the stud 12 and balls 19 in place. In the last-mentioned view it will be seen that the wheels are formed with faces 85 25 of so considerable width that the wheels will not cut into the boxes or packages conveyed on them even if they are as heavy as the wheels and studs will stand.

In using the device the blocks or supports 90 7 may be made or selected of such increasing height as the topography and the desired speed of the motion may require. The track-rails may of course be bent sidewise either in the making of them or by swinging 95 gradually the sections to one side, leaving the joint 8 unhooked and partly separated on the other or longest side of the track, or at the end of a straight line of track another line may be started in any direction.

The means for elevating the goods or boxes to the necessary height for starting same on the conveyer need not here be described, as they are usually already provided, either as hoisting devices, elevators, or inclines upon 105 which the cars enter to deliver the goods, or especially short elevators or hand-power may be used.

Having thus described my invention, what I claim, and desire to secure by Letters Patent, is—

1. A gravity-conveyer comprising inclined

rails with horizontal journals for wheels or rollers; wheels, sheaves or rollers on the journals overlapping each other, every other wheel being grooved and the next wheel 5 narrow enough to revolve with its edge in such groove.

2. A gravity-conveyer comprising inclined rails with horizontal journals for wheels or rollers; wheels, sheaves or rollers on the journals overlapping each other, every other 10

wheel being grooved, and the next wheel narrow enough to revolve with its edge in such groove, and ball-bearings in said wheels.

In testimony whereof I affix my signature in presence of two witnesses.

CHARLES O. HILER.
